UNITED STATES PATENT OFFICE.

JOSEPH YATES, OF MOTT HAVEN; NEW YORK.

IMPROVED APPARATUS FOR THE MANUFACTURE OF IRON.

Specification forming part of Letters Patent No. 41,806, dated March 1, 1864.

To all whom it may concern:

Be it known that I, JOSEPH YATES, of Mott Haven, in the county of Westchester and State of New York, have invented certain new and useful Improvements in Furnaces or Apparatus used in the Manufacture of Iron and in other Metallurgical Operations; and I hereby declare that the following is a full, clear, and exact description of the same.

My invention, although relating more particularly to the manufacture of malleable or wrought iron, whether the same is obtained directly from the ore—that is to say, without previous conversion into pig metal—or indirectly—*i. e.*, by first submitting the ore to a smelting and refining process—is also applicable in general to such other metallurgical operations in which reverberatory furnaces are used; and the object of my invention is to elevate the temperature of furnaces without consuming a large quantity of fuel or increasing the blast, thereby effecting the operations in the furnace in less time than they could otherwise be effected; also, to preserve against deterioration such parts of the reverberatory furnace which heretofore were liable to be destroyed by exposure to intense heat, necessitating frequent stoppages for repairs, which in metallurgical operations is a fatal objection; and my invention consists, first, in forming the hollow fire-bridge of cast-iron, and connecting the same, by means of an india-rubber or other hermetic joint located upon the outside of the furnace, with tubes or their equivalent conveying the blast of air to, through, and from the fire-bridge; secondly, in the combination of the hollow cast-iron fire-bridge and tubes for conveying the blast to and from the said bridge with intermediate hollow cast-iron side wall-pieces, so that the sides in contiguity with the bridge shall, by a blast of air through them, be kept cool and preserved from injury; thirdly, in iron-casing that portion of a reverberatory furnace which is above the sole by making the sole of cast-iron plate flanged to clasp the armor-plate, substantially as herein-after more fully shown and explained; fourthly, in combining with a reverberatory furnace operated by heated blast of air a reducing oven or apparatus so arranged relatively to each other that the flame and heated gases of the former shall be discharged into the latter at the temperature requisite for the reduction

of the ore, substantially as hereinafter more particularly explained; fifthly, in forming in a furnace operated by a heated blast a double reverberatory roof, and in so combining the same with a reducing-oven that the contents of the latter may be discharged directly upon the sole of the furnace under the reverberatory roof most distant from the fire, substantially as hereinafter more fully explained.

Although this invention is applicable to any reverberatory furnace, I shall confine myself to a description of an apparatus embodying the principles thereof as adapted to the making of malleable or wrought iron directly from the ore.

In the accompanying drawings, Figure 1 is a perspective view of the whole apparatus. Figs. 2, 3, 4 are sectional views according to planes indicated by the section-lines A. B C D, and Fig. 5 is a detail view of the bridge and pipe connection.

In said figures, A is a reducing-oven consisting of a series of chambers composed of vertical walls and horizontal or inclined tables, (called "reducing-tables,") which intercommunicate in such manner that the heated gases or flame issuing from the furnace shall pass under and over each table. When the furnace is in operation, the tables are charged with a mixture of powdered coal and ore, and exposed to a high degree of heat, under the influence of which the ore is duly reduced. Each table may be discharged through funnel-shaped tubes directly into the furnace, and the mass of reduced ore collected on the sole thereof is worked by the operators until the requisite consistency is acquired, when it is brought under the first reverberatory roof or arch, where it is converted into a bloom in the manner well known in iron-making. The whole apparatus is supplied by a forced blast of air from a fan delivered into the closed ash-pit, so that the proper high degree of temperature may be speedily attained, and access of air other than that blown into the furnace, and which in passing through the fire is freed of its oxygen, may be avoided.

The reverberatory furnace as constructed consists of the usual grate of fire-bars separated by a bridge from the hearth, and the flame from the fuel passing over the bridge is deflected by the low arch above on the hearth, and finally passes off through a chimney into the

open air or through flues into an oven or other apparatus in which the waste heat is utilized.

In reverberatory furnaces in which an extended hearth is used surmounted by a double-arched roof, and particularly when worked under pressure, the heat and the volume of gases accumulated in the furnace are such as to injuriously affect its structure by causing the melting of the bridge and interior side walls contiguous therewith, and by bulging and bursting of the side walls, notwithstanding of iron braces and ties. On the other hand, the great heat and pressure in the furnace are only obtained at great cost of fuel, a great amount of caloric being absorbed by the injection of cold air upon the fuel. In my improved furnace I have provided against excessive destructibility by a method of constructing a reverberatory furnace, producing, with coal and a blast of air, the requisite degree of heat without destroying itself, and produce a great saving of fuel by the employment of a heated blast of air.

The furnace shown in the accompanying drawings has many features in common with the ordinary reverberatory furnaces. Its form, dimensions, and proportion—the result of many experiments—have particular reference to furnaces in which the particles of iron derived from ore reduced in a reducing-oven are united and welded together to form a bloom. The fire-place B is built of fire-brick, incased in cast-iron plates firmly united by bolts or tie-rods, so as to prevent them from starting asunder. In front at C is the fire-door, hinged at its upper side to a frame of the stoke-hole, which is so beveled as to cause the door by its gravity to close it. At the side and below the grate is the door to the ash-pit, through which the ashes are from time to time removed. The fire-bars D are supported by cross-bars E, secured in the side walls.

The fire-bridge, which separates the fire-place from the hearth, is supported by a wall of ordinary or refractory brick, and is composed of a cast-iron tube, F, extending to the outside from front to rear of the furnace. With this hollow cast-iron fire-bridge are combined, by means of curved cast-iron pipes or spherical caps G, two pieces of side walls, H, made hollow, of cast-iron, of such exterior form as to adapt themselves to the interior and exterior surface of the furnace. These cast-iron side pieces are thus formed of vertical externally-plane and internally-curved plates, united on top and bottom by horizontal plates, and extend vertically from the hearth to a level with the top of the fire-bridge, and horizontally from the fire-bridge to the working or balling door I. The outer plates are perforated at or near the extreme end toward the balling-door, and are connected with pipes descending along the side of the furnace, the one on the one side to be connected with a pipe leading from a fan-blower, and the other on the opposite side to connect with a tuyere, discharging its blast into the closed ash-pit. The caps or curved tubes form a hermetic joint with both the cast-

iron bridge and side wall-pieces by the interposition between the flanges of vulcanized india-rubber packing R. The cold-blast, it will be understood, passes up the pipe K, enters the side piece at L, and is forced through the cap G into and out of the fire-bridge, then through the other cap, G', and the opposite side piece down the pipe M, and is finally conveyed to and discharged under the grate into the fireplace. By this arrangement fresh air is constantly supplied to the parts most exposed to heat, and heated air, on the other hand, is supplied to the cold fuel.

The hearth N is made of one or more cast-iron plates having upright flanges at the sides which correspond to the front and rear of the furnace. These cast-iron plates extend transversely to the outside of the furnace, and are supported by a brick wall having air-holes O, provided with suitable doors for regulating the temperature underneath the hearth. The interior side walls of the furnace are built up on the hearth-plate of fire-brick, and are incased in an armor of cast-iron plates clamped at their under sides by the flanges of the hearth-plate and at the upper sides by tie-rods. By this arrangement the furnace can withstand considerable internal pressure without danger to the integrity of the structure. The side walls and armor of the furnace have in front two openings provided with sliding doors, which I denominate, respectively, the "working-door" and the "balling-door." The arched and reverberatory roof, which is sprung from one side wall to the other, terminates in flues whereby the furnace is connected with a reducing-oven, and a hopper or channel is so arranged in relation to the furnace and the oven as that the tables may be discharged through it directly into the furnace. This hopper is provided with two sliding register-valves, which are kept shut during the intervals of charge, and are opened when the charge is ready to be dropped. The frequent burning out of a portion of the end wall, W, of the furnace by the flame constantly striking it necessitates the frequent removal of some of the fire-brick and the insertion in their stead of fresh fire-brick. To effect this with ease and without stoppages, I form a small opening in the end wall and fill it with fire-brick or a fire-plug, which may be readily removed and replaced.

Having now fully described my invention and the manner in which the same is or may be carried into effect, I shall state my claims as follows:

1. Forming the hollow fire-bridge of cast-iron, and connecting the same by means of an india-rubber or other hermetic joint located upon the outside of the furnace, with tubes or their equivalent for conveying the blast of air to, through, and from the fire-bridge, substantially as herein set forth.

2. The combination of the hollow cast-iron fire-bridge and tubes for conveying the blast to and from said bridge with intermediate hol-

low cast-iron side wall-pieces, so that the sides in contiguity with the bridge shall, by a blast of air through them, be kept cool and preserved from injury, substantially as herein set forth.

3. Iron-casing that portion of a reverberatory furnace which is above the sole by making the sole of cast-iron plate flanged to clasp the armor-plate, substantially as hereinbefore described.

4. Combining with a reverberatory furnace operated by heated blast of air a reducing oven or apparatus so arranged in relation to each other that the flame and heated gases of the former shall be discharged into the latter at the temperature requisite for the reduc-

tion of the ore, substantially as herein set forth.

5. Forming in a furnace operated by a heated blast a double reverberatory roof, and so combining the same with a reducing-oven that the contents of the latter may be discharged directly upon the sole of the furnace under the reverberatory roof most distant from the fire, substantially as set forth.

In testimony whereof I have signed my name to this specification before two subscribing witnesses.

JOSEPH YATES.
